COMBINED FRAME, DRIVE MECHANISM AND FACE AND HANDS FOR A CLOCK

Ralph D. Thomas, 1412 Drumcliff Road,
Winston-Salem, N.C. 27103

Filed June 17, 1965, Ser. No. 85,787

Term of patent 14 years

(Cl. D42—7)

FIG. 1 is a front perspective view of a combined frame, drive mechanism and face and hands for a clock embodying my new design; FIG. 2 is a left-side elevational view thereof, a fragment of the pendulum ball being broken away for convenience of illustration; and FIG. 3 is a top plan view thereof.

Portions of the pendulum shaft and weight-support cable are broken away to indicate variable length. The essential features of my design are shown in full lines.

I claim:

The ornamental design for a combined frame, drive mechanism and face and hands for a clock, as shown and described.
